R. F. Osgood.

UNITED STATES PATENT OFFICE.

JOHN H. WILLIAMS, OF ALBION, NEW YORK.

ATTACHMENT FOR RAILWAY-CARS.

SPECIFICATION forming part of Letters Patent No. 388,100, dated August 21, 1888.

Application filed December 19, 1887. Serial No. 258,394. (No model.)

To all whom it may concern:

Be it known that I, JOHN H. WILLIAMS, of Albion, in the county of Orleans and State of New York, have invented a certain new and 5 useful Improvement in Attachments for Railroad-Cars; and I do hereby declare that the following is a full, clear, and exact description of the same, reference being had to the drawings accompanying this specification.

10 My improvement consists of extensible attachments to railroad-cars, capable of being folded in compact form at the sides of the cars and of being extended and forming an inclosure to the cars at stations when the cars are 15 at rest, so as to prevent ingress to the cars, except at a gateway formed at the outer ends of the extensions. At large and populous stations the tracks at the passenger-depots are usually inclosed by a permanent fence or rail- 20 ing. At small stations this is frequently impracticable, and the object of my invention is to combine with the cars extensible sections which can be stretched out, forming a V, inclosing the entrances to the cars, the whole con- 25 structed, arranged, and operating as herein-after more fully described.

In the drawings, Figure 1 is a diagram showing a plan view of a train of cars minus the locomotive, tender, and baggage-car, and exhibiting the appliances which constitute my 30 invention, the same being extended to inclose the entrances to the cars. Fig. 2 is a side elevation of a portion of one of the cars, showing the appliance folded in place at the side of the car. Fig. 3 is an enlarged elevation of a portion of the extensible fence. Fig. 4 is a perspective view of the joint at the end of the fence that is attached to the car. Fig. 5 is a perspective view of the supporting standard 35 or foot at the outer end of the fence.

A, B, and C, Fig. 1, indicate three passenger-cars of a railway-train, which are of ordinary construction.

My improvement is as follows: D D are sections of extensible fence, made in the form of lazy-tongs, consisting of bars *a a*, crossing each other in angular direction and pivoted at the ends and in the center, as shown in Fig. 3. These bars when folded close up in very compact form and occupy but little space. When 45 extended, they occupy a good deal of length. Four of these sections are attached to each

car, two on each side and near the ends, but back of the platforms and steps of the car. At one end they are hung to the car by suitable joints, so as to be capable of being swung around like a gate. One form of joint is shown 55 in Fig. 4, in which *b* is the part to which the bars are attached and *c* is the socket that turns horizontally on a hook, *d*, forming part of a spider, *k*, attached to the under side of the car, said hook forming the permanent knuckle of the hinge. By this means the section can be swung around like a gate. The part *b* is hinged to *c* by a pivot, *f*, so as to turn vertically. By 60 this means the outer end of the extensible section can be raised. The outer end of the section D has a hook, *g*, that catches on a catch, *m*. The catch *m* forms part of a portable standard, *L*, having three feet, *p p p*, at the bottom, 65 by which it is self-supporting, and a hook, *r*, at the top, by which it can be hung under the car when not in use. In use, the train-man takes the support in hand and carries it out where the fence is to be extended and hooks the end 70 of the fence to it, by which means the outer end of the fence is self-supporting. When hung in place and folded up, these sections 75 rest at the side of the car and occupy the vertical space between the bottom of the car and 80 the ground, but raised from the ground, so as not to come in contact with any obstacle.

The operation is as follows: When not in use, the sections are folded up, as above described, and are out of the way. On arrival 85 at a station the front door of the front car and the rear door of the rear car are locked. The rear section D of the front car and the front section D of the rear car are then extended out in V form, as indicated in Fig. 1, entrance 90 only being left at the apex. This work is done by the train-men. This inclosure covers the entrance to all of the platforms open to the cars, and passengers can reach the cars only through such inclosure. The extensible sections 95 can be made long enough to meet in trains of any usual length. Three cars are shown in the drawings; but it is applicable to a greater number. In trains of very great length two or more of the V's may be formed, 100 the doors being locked between the V's.

Another use of the extensible sections is to close the exit between the cars on one side while the other is in use. One of the sections

D at the end of one of the cars is swung round and extended across the opening between the cars. On many railroads most of the passenger-depots are on one side of the road. The 5 exits on the opposite side can in that case be kept closed.

In some cases the extensible fences are provided at the top and on the under side with pivoted links *h h*, which, when the fence is extended, straighten and make a straight top and center to the fence, thereby closing the passage more effectively and adding strength. When the fence is closed, these links fold down and drop behind the bars.

15 Having described my invention, what I claim as new, and desire to secure by Letters Patent, is—

1. The combination, with two or more cars of a railway-train, of extensible sections of 20 fence attached, respectively, at the sides of the cars and capable of being extended outward

in V form, to inclose the entrance to said cars, in the manner and for the purpose specified.

2. The combination, with a railroad-car, of 25 a section of extensible fence composed of pivoted bars in the form of lazy-tongs, with pivoted links connecting the tops and center of the bars, as and for the purpose specified.

3. The combination, with the extensible sections D of fence having a hook, *g*, at their 30 outer ends, of the portable standard L, provided with feet, to be self-supporting, and with a catch to receive the hook *g*, as and for the purpose specified.

In witness whereof I have hereunto signed 35 my name in the presence of two subscribing witnesses.

JOHN H. WILLIAMS.
